UNITED STATES PATENT OFFICE.

ELIJAH JOHN FADER, OF CALGARY, CANADA.

DREDGING-BUCKET.

SPECIFICATION forming part of Letters Patent No. 546,698, dated September 24, 1895.

Application filed January 28, 1895. Serial No. 536,755. (No model.)

To all whom it may concern:

Be it known that I, ELIJAH JOHN FADER, miner, residing at the town of Calgary, in the district of Alberta, in the Northwest Territories, in the Dominion of Canada, have invented a certain new and useful Dredging-Bucket; and I do hereby declare that the following is a full, clear, and exact description of the same, reference being made to the accompanying drawings, in which—

Figure 1 is a plan of bucket, longitudinally. Fig. 2 is a plan of bucket in operation on a river-section embodying my invention.

The first part of my invention relates to the bucket and its construction in such a manner that in a river-current, with the aid of certain cables, it will swing out into the stream automatically, having propeller-flanges attachable for lighter currents and reversible, so that it can be worked from either bank of a river or stream. It also has a funnel-shaped mouth, which on being drawn by that end ashore dips and forces its way into the river-bed, thus filling the bucket with the material scraped from the bed of river, this funnel-shaped mouth to have teeth or sharp spikes bolted on when necessary in working on a hard-clay strata. Bucket-barrel and funnel-flange are each made in two pieces and bolted together, so that the whole can be taken apart and packed on horses to transport across mountainous country. It also has a bottom with hinge and spring latch, so that when hoisted its contents can be emptied by knocking open the latch.

The second part of my invention relates to the method of working this bucket from either bank of a river by attaching to the swivel at the end of draw-irons at the mouth or open end of bucket a hook and pulley, through which works a cable having one end securely fastened on shore and the other end working in a winch on same shore. To a swivel on the other or bottom end of bucket is attached a rope or cable fastened to the opposite shore or anchor out in the stream, if more suitable, and of sufficient length to allow the bucket to be hauled ashore and emptied, making use of the river-current acting on the bucket-propeller flanges and last-mentioned rope or cable to give to the bucket a revolving pro-

gressive motion over the bottom or bed of river, swinging it out from shore into position, and to hold it against bed of river as it is drawn ashore by winch.

In Fig. 1 of drawings, A is the barrel or bucket, of cylindrical form, three feet long, with a diameter of two feet four inches, made of roll-plate, steel, iron, or aluminium, in two sections, bolted together, as shown at 11 and 55 at opposite side of barrel. B is the funnel-shaped dipping-flange, made in two sections and bolted together, having a width of ten inches, a diameter at outer edge of three feet, and inner edge bolted to one end of barrel A. 60 C is the bottom at the other end of barrel, opening with a hinge on barrel opposite the spring-latch K, which fastens the bottom when closed. G is a swivel-ring on bottom for attaching cable. D D D are the propeller-flanges, bolted to bucket by braces H H H. Each of these flanges encircles one-third of circumference of barrel, are four inches wide near end at B, and eight inches wide at end at C. They can be reversed to L' L' and 65 bolted to barrel, so that bucket can be worked from either side of river. E E E are the draw-irons, three feet long and one inch thick, bolted to barrel inside of funnel or dipping-flange B, having a swivel-ring F at outer end 70 for attaching cable.

Fig. 2 of the drawings represents a section of river with current running in the direction as shown by arrow, and shows the method of working the bucket H. At A it is being 85 swung out from shore C D to its position at B, when it is ready to be drawn ashore by the cable E F on the pulley I, one end fastened at M and the other wound on winch G. K is the rope or cable fastened on shore at L and 90 to rear or bottom end of bucket, on which it swings out into the stream by paying out the cable E F. If necessary, the cable K can be supported by one or more buoys or lighters, and should the bucket foul on a boulder or 95 other obstruction it can be relieved by attaching end of cable at M to the lighter N, and by means of the winch G running out the lighter N to the bucket. This failing, bucket can be relieved by the cable K. After bucket is 100 hauled ashore it can be hoisted into position over sluice-box P by means of a snatch-block

on triangle O, and bottom of bucket thrown open by knocking up the latch.

What I claim as my invention, and desire to secure by Letters Patent, is—

- 5 1. A dredging bucket of cylindrical form with or without the propeller flanges D, D, D, which are required only in slack currents, having a funnel-shaped dipping flange B, at mouth of bucket barrel A, which serves to fill bucket when drawn by that end on river bed, and having two swivels, one F, at end of draw irons E, E, E, and another G on bottom C allowing bucket to revolve over river bed, substantially as and for the purpose herein-
10 before set forth.
- 15 2. The combination of the bucket with the cable E, F, having one end fastened on river

shore at M, working through pulley I and the other end to winch G which hauls bucket ashore, and with the cable K one end of which 20 is fastened on opposite shore at L or to an anchor out in the stream and the other end to swivel ring on bottom of bucket when by paying out the cable E, F the river current acting on cable K and on bucket revolves and swings 25 the bucket out into position ready to be filled and drawn ashore, substantially as and for the purpose hereinbefore set forth.

Ottawa, Ontario, January 22, 1895.

ELIJAH JOHN FADER.

In presence of—

S. C. LAROSE,
A. BLAIS.
